METHOD OF MAKING MERCURY SWITCHES

Carl H. Larson, Elkhart, Ind., assignor to The
Adlake Company, a corporation of Illinois

Application January 3, 1933, Serial No. 649,819

6 Claims. (Cl. 200—152)

The usual method of making mercury switches is to take an open switch envelope into which electrodes have been sealed, place a quantity of mercury in the envelope along with any other parts which are to go into the switch, evacuate the envelope, introduce a suitable gas fill, and then seal-off the open end of the envelope. The switch is then tested, and if it fails to perform satisfactorily, the seal is broken and the necessary 10 adjustments are made, such as varying the amount of mercury, repositioning the electrodes, etc. The envelope is again evacuated, filled with an inert gas and then sealed off and another test is made. This process of opening and closing 15 the switch envelope is repeated as often as necessary to obtain the desired characteristics of the switch.

Certain kinds of mercury switches require greater accuracy in their manufacture than 20 others, because of more stringent service requirements. For example, switches which are used in relays must be highly sensitive so that the pickup and drop away values of the relay will not vary. Time delay switches also require great 25 accuracy in their manufacture because of the fine adjustments which must be made to obtain given time delays.

In the switch which has been chosen to illustrate the method of this invention, a hollow 30 plunger is placed within a vertical switch envelope into which suitable electrodes have been sealed, and by magnetically manipulating the position of the plunger in the envelope, the mercury level may be controlled to open or close a circuit 35 through the electrodes. The top of the plunger is closed except for a small restricted opening into which a tapered plug is fitted. When the plunger is lifted by energizing the associated coil, mercury is carried up in the 40 plunger and slowly recedes as the gas pressure within the plunger is equalized with the outside pressure by gas entering the plunger through the restricted hole at the top of the plunger. After a given time interval, the two pressures 45 are fully equalized and the central electrode is uncovered, thus breaking the circuit. Similarly when the plunger is dropped by de-energizing the coil, gas is trapped within the plunger holding the mercury away from the central electrode 50 until sufficient gas has escaped through the restricted hole to equalize the pressures on the inside and outside of the plunger. Obviously the time delay is governed by the tightness of the tapered plug fit.

55 It is physically impossible to determine what

the time delay in such a switch will be by testing the switch in open air, prior to inserting the gas fill and sealing. This is due to the fact that gases commonly used for fills pass through restricted orifices much faster than air. Other 60 variables, such as humidity, viscosity of the mercury, and mercury friction also prevent accurate determinations of time delay prior to sealing.

Even if it were possible to control conditions of humidity, rates of gas leakage, viscosity, etc. 65 it would still be undesirable to test the switch in the open atmosphere. A single operation of the circuit breaker in the open air, would so contaminate the mercury that it would cause the switch to be erratic in later operation. 70

The principal object of the present invention, therefore, is to provide a method and apparatus for making mercury switches that avoids the necessity of breaking open the switch seals in order to make adjustments; that enables greater 75 accuracy to be obtained in securing given time delays; that saves material, reduces the cost of manufacture, and enables switches to be made in less time than heretofore possible; and that effects these desirable results by the use of simple 80 apparatus.

Further and other objects and advantages will become apparent as the disclosure proceeds and the description is read in conjunction with the accompanying drawing, in which 85

Fig. 1 is a semi-diagrammatic view showing a switch in the process of manufacture according to the teachings of this invention;

Fig. 2 is a sectional view showing a completed switch in operative position within a relay coil; 90 and

Fig. 3 is a perspective view of the adjustable plug in the top of the switch plunger.

The description of a specific switch structure and a preferred method are for the purpose of disclosure only and should not be construed as imposing limitations upon the appended claims except as may be required by the prior art.

An understanding of the method of manufacturing mercury switches according to this invention will be facilitated by first describing the completed switch and the manner in which it is used. Referring, therefore, to Fig. 2, it will be seen that the switch comprises a vertical glass envelope 10 into the bottom of which electrodes 11 and 12 are suitably sealed. A glass sleeve 13 insulates the electrode 11 from the mercury fill 14 up to a point just below the top of the electrode. The electrode 12 is uninsulated and is constantly immersed in the mercury. 105 110

A plunger, or displacer 15, which may be made of iron or iron and some other material, displaces sufficient mercury when in the position shown in Fig. 2 to cover the top of the electrode 11 and thus establish a connection between the electrodes 11 and 12. When the plunger is lifted by energizing the coil 16 which is telescoped over the switch, the mercury recedes a sufficient amount to uncover the electrode 11 and break the circuit through the electrodes 11 and 12.

The coil 16 is wound on a spool 17 having a central opening 18 of sufficient diameter to receive pole sleeves 19 and 20. The pole sleeves may be adjusted vertically within the spool and are clamped in place by clips 21 which are secured to the ends of an iron yoke 22. The yoke increases the operating efficiency of the coil by furnishing an exterior iron circuit and preferably is laminated for use with alternating current. The position of the sleeves 19 and 20 within the spool 18 determines the position of the air gap in the magnetic circuit. When the coil is energized, the plunger 15 rises in its effort to close the air gap and the mercury level drops in the envelope, thereby uncovering the electrode 11.

The top of the plunger 15 is closed except for a small opening 23 into which a tapered plug 24 is tightly fitted. The plug is shown more clearly in Fig. 3. Instead of a single restricted opening in the top of the plunger, a porous material, such as a ceramic, might be substituted for the plunger head.

Springs 25 and 26 cushion the plunger against hard impacts with the top and bottom of the switch envelope. Preferably the switch plunger has the bulk of its mass above the mercury level in order to make the potential energy of the plunger when in its raised position substantially equal to the magnetic energy necessary to raise the plunger from its depressed position.

Obviously the tighter the fit between the plunger 15 and the plug 24, the less will be the gas leakage between the interior and exterior of the plunger. It is this adjustment which must be made with great accuracy in order to obtain given time delays.

Referring now to Fig. 1, which illustrates preferred apparatus for use of the method, the switch envelope 10 with electrodes 11 and 12 sealed into the bottom, is first filled to a level 27 with mercury. The plunger 15 is then placed in the envelope with the plug 24 approximately positioned in the opening 23 according to the time delay that is required. The envelope is then ready for evacuation.

A vacuum pump diagrammatically shown at 28 is joined by a suitable connection 29 to a three-way glass stop cock 30, which in turn is connected to a high frequency discharge device 31 and a piece of glass tubing 32 having a restricted portion 33. The connection between the envelope and glass tubing 32 is made by a heavy piece of rubber tubing 34, and a similar piece of rubber tubing 35 connects the discharge device 31 with the upper end of the tubing 32. Suitable connections 9 and 36 join the discharge device 31 with the stop cock 30 and the stop cock with the connection 29, respectively.

The stop cock is provided with a plug 37 with two holes 38 and 39 bored at an angle adapted to connect the nipple 40 with the nipple 41, or the nipple 42 with the nipple 41, according to the position of the plug. In the position shown in Fig. 1, the nipple 41 is connected to the nipple 42.

The high frequency discharge device 31 includes a spark coil 43 connected to a suitable source of current and having one lead 44 grounded and the other lead 45 connected to an electrode 46. When the coil 43 is in operation, the degree of vacuum in the system can be determined by the color of the discharge. The color ranges from a deep purple when the system is partially evacuated to a light blue when a high vacuum has been obtained.

After the vacuum pump 28 has reduced the pressure in the switch envelope a sufficient amount, the stop cock 30 is rotated through 180° to the position shown in Fig. 1. In this position, a suitable gas fill is introduced into the envelope from the container 47. The gas may be helium, hydrogen, nitrogen, or any other suitable gas.

The top of the container 47 is fitted with a valve 48, and gauge 49, the former for regulating the pressure of the gas being emitted from the container, and the latter for registering that pressure. The nipple 40 of the stop cock 30 is joined by a connection 50 with the container 47 and a valve 51 is provided in the connection for regulating the flow of gas therethrough. A gauge 52 interposed between the valve 51 and the stop cock registers the pressure in the envelope 10.

In practice, the envelope is evacuated and filled with gas from the container several times in order to make sure that all air has been removed from the envelope. The envelope is finally filled with gas at a pressure of about five pounds less than atmospheric pressure, and then the envelope is sealed off at 33. This forms a temporary switch structure in which the actual conditions of use are exactly duplicated, and the switch may then be inserted in a suitable coil for testing. If it is found that the mercury level is too high or too low, or the plug 24 does not provide the required time delay, the connection at 34 may be broken, the plunger removed and the necessary adjustments made. Thereafter the process is repeated until the switch functions according to specification. The switch envelope 10 is then sealed off in the usual manner below the connection 34.

Although it is usually desirable to seal off the temporary switch structure at 33 so as to conduct the tests in a more convenient place, it is not at all necessary that it be done. It is obvious that by merely closing the stop cock 30, it is possible to test the switch by placing a solenoid in appropriate position over the envelope. In such case the tubing 32 is unnecessary.

The process is readily adaptable to mass production methods. For example, a number of switch blanks may be placed on a rotary table for automatic evacuation and filling, after which tests may be made on the individual switches without removing them from the table. Whenever a switch is found to have the proper operating characteristics, it may then be sealed off and removed from the table.

Various modifications of the process will be apparent to those skilled in the art. For example, it is not essential, in every instance, that the envelope be separated from the associated apparatus to make adjustments in the switch when tests have found them necessary, it being possible to provide suitable means within the envelope for making the adjustments.

The type of slow acting relay shown in Fig. 2 of the drawing, but not herein claimed, is the

subject of a copending application filed July 6, 1932 and bearing Serial Number 621,088.

What I claim is:

1. A method of making mercury switches which includes taking an open switch envelope into which electrodes have been sealed, placing a quantity of mercury and a displacer in the envelope, temporarily connecting the open end of the envelope through a piece of glass tubing with apparatus for evacuating the envelope and for thereafter filling it with an inert gas and then sealing off the tubing to produce a temporary switch structure which duplicates the characteristics of a finished switch, testing the temporary switch and adjusting it to specification, and finally sealing off the open end of the envelope to form a completed switch. 80
2. The method of making a time delay mercury switch of the type in which the escapement of gas through one or more restricted passages constitutes the timing element, said method including taking an open switch envelope into which electrodes have been sealed, placing a quantity of mercury and a mercury displacer in the envelope, connecting the open end of the envelope with apparatus adapted to produce in the envelope the gaseous conditions which exist in a finished switch, producing such conditions, and then testing the switch and adjusting the size and/or number of passages through which the gas escapes to obtain predetermined switch characteristics, and then sealing off the open end of the switch. 95
3. The method of making a mercury switch which includes taking an open switch envelope into which electrodes have been sealed, placing a quantity of mercury and a mercury displacer in the envelope, connecting the open end of the envelope, through a piece of glass tubing, with apparatus adapted to produce in the envelope the gaseous conditions which exist in the finished switch, and then sealing off the glass tubing to produce a temporary switch structure which duplicates the characteristics of the finished switch, testing the temporary switch and adjusting it to specification, and finally sealing off the 100
4. The method of making a mercury switch which includes taking an open switch envelope into which electrodes have been sealed, placing a quantity of mercury and a mercury displacer in the envelope, connecting the open end of the envelope, through a piece of glass tubing having a restricted passage, with apparatus adapted to produce in the envelope the gaseous conditions which exist in the finished switch, and then sealing off the restricted portion of the glass tubing to produce a temporary switch structure which duplicates the characteristics of the finished switch, testing the temporary switch and adjusting it to specification, and finally sealing off the open end of the envelope to form a completed switch. 105
5. The method of making mercury switches which includes taking an open switch envelope into which electrodes have been sealed, placing a quantity of mercury in the envelope, connecting the open end of the envelope with apparatus adapted to produce in the envelope the gaseous conditions which exist in the finished switch, producing such conditions, and then testing the switch, adjusting the mercury level and other parts until proper switch characteristics are obtained, and then sealing off the open end of the envelope. 110
6. The method of making mercury switches which includes taking an open switch envelope into which electrodes have been sealed, placing a quantity of mercury in the envelope, connecting the open end of the envelope with apparatus adapted to produce in the envelope the gaseous conditions which exist in a finished switch, producing such conditions and then testing the switch while the envelope is still connected to the apparatus, removing the connection and adjusting the mercury level and other parts, connecting the envelope to the apparatus again and repeating the subsequent steps until proper switch characteristics are obtained, and then sealing off the open end of the envelope. 115

CARL H. LARSON.
